United States Patent Office

Des. 183,225

Patented July 15, 1958

183,225

CARPET SCRUBBING MACHINE

Harry D. Rensch and Herbert W. Harris, Racine, Wis.,
assignors to Racine Industrial Plant, Inc., Racine, Wis.,
a corporation

Application November 19, 1956, Serial No. 43,823

Term of patent 14 years

(Cl. D9—2)

Figure 1 is a perspective view of a carpet scrubbing machine, showing our new design; and

Figure 2 is a perspective view of the machine looking from the opposite end thereof.

We claim:

The ornamental design for a carpet scrubbing machine, as shown.
